EX

OR D 19•837

JOHN T. HOLDER, OF GENEVA, FLORIDA.

DESIGN FOR A RUSTIC TABLE OR STAND.

Design No. 19,837, dated May 13, 1890.

UNITED STATES PATENT OFFICE.

JOHN T. HOLDER, OF GENEVA, FLORIDA.

DESIGN FOR A RUSTIC TABLE OR STAND.

SPECIFICATION forming part of **Design No. 19,837**, dated **May 13, 1890**.

Application filed January 18, 1890. Serial No. 337,387. Term of patent 7 years.

To all whom it may concern:

Be it known that I, JOHN T. HOLDER, of Geneva, in the county of Orange and State of Florida, have invented a new and original Design for a Rustic Table or Stand, of which the following is a specification, reference being had to the accompanying photograph, forming a part thereof, which photograph represents a perspective view of a table or stand embodying my design.

The design consists of a disk-like figure A, represented as upheld by V-shaped figures B,

having a stem-like appearance, and leaf-like figures C, of a palmetto type, arranged between rough branch-like figures D, which leaf and branch like figures seemingly form a portion of the main figures B.

I claim—

A design for a table or stand, substantially as herein shown and described.

JOHN T. HOLDER.
